UNITED STATES PATENT OFFICE.

CHARLES HENRI BENOIT, OF SAN JOSÉ, CALIFORNIA.

SHUTTLE FOR SEWING-MACHINES.

SPECIFICATION forming part of Letters Patent No. 397,269, dated February 5, 1889.

Application filed September 16, 1887. Serial No. 249,879. (No model.)

To all whom it may concern:

Be it known that I, CHARLES HENRI BENOIT, of San José, in the county of Santa Clara and State of California, have invented a new and Improved Sewing-Machine Shuttle, of which the following is a full, clear, and exact description.

Reference is to be had to the accompanying drawings, forming a part of this specification, in which similar letters of reference indicate corresponding parts in all the figures.

Figure 1 represents an elevation of a part of the head of a sewing-machine, showing the needle-bar, presser-bar, take-up, cloth-plate, (in section,) the shuttle, and the shuttle-carrier. Fig. 2 is a plan view of the shuttle, and Fig. 3 is a perspective view of the spring.

The invention will first be described in connection with the drawings, and then pointed out in the claims.

The needle-bar A, presser-bar B, cloth-plate C, and shuttle-carrier D are of the usual construction.

The shuttle G is enlarged at f and f' to receive a large bobbin and a large quantity of thread; and in order that the shuttle may pass readily through the loop I elevate the point f² and form the lower part of the shuttle with a curve, f³, of a comparatively short radius, reaching from the point to the bottom line of the shuttle. The curve f⁴ of the shuttle, at the upper part thereof, reaching from the point back, is of much larger radius than the curve f³, so that it is practicable to make the shuttle very large to hold a large quantity of thread, and yet it will enter and pass the loop readily, and, owing to the elevation of the point f², the needle h may be set one-

eighth of an inch higher than with the ordinary form of shuttle and take-up.

The tension-spring j is formed with the tongue j' and slot j² to give tension to the lower thread. The thread is entered beneath the spring j under the tongue k. The said spring is formed with a projection at its rear end, which projection is under the tongue k, and is bent downward and forward to form a hook, l, which lies in a small recess, l', made in the body of the shuttle. The thread from the shuttle is passed between the tongue k and hook l, and thence forward under the spring, the hook l serving to prevent the thread from being drawn back accidentally from the spring j.

Having thus described my invention, what I claim as new, and desire to secure by Letters Patent, is—

1. The tension-spring j, provided with the tongue j' within the body of the spring, the hook l, projecting from the rear of the spring and having its end bent downward and forward, and the tongue k, projecting from the rear end of the spring over the hook l, substantially as herein shown and described.

2. The combination, with a recessed shuttle, of the spring j, provided with the tongue j' within the body of the spring, the hook l, projecting from the rear end of the spring and having its end bent downward and forward into the recess of the shuttle, and the tongue k, projecting forward over the hook l, substantially as herein shown and described.

CHARLES HENRI BENOIT.
